(57) **CLAIM**

The ornamental design for a watch, as shown and described.

DESCRIPTION

1.1 is a perspective view of a first embodiment of a watch showing my new design;

1.2 is a front view thereof;

1.3 is a back view thereof;

1.4 is a right side view thereof;

1.5 is a left side view thereof;

1.6 is a top view thereof;

1.7 is a bottom view thereof;

2.1 is a perspective view of a second embodiment of a watch showing my new design;

2.2 is a front view thereof;

2.3 is a back view thereof;

2.4 is a right side view thereof;

2.5 is a left side view thereof;

2.6 is a top view thereof; and

2.7 is a bottom view thereof.

1 Claim, 14 Drawing Sheets
